Dana W. Mox, Glenview, Ill., assignor to Hanson Scale Company, a corporation of Illinois

Filed Jan. 15, 1968, Ser. No. 10,155

Term of patent 14 years

U.S. Cl. D52—10
Int. Cl. D12—08

FIGURE 1 is a top plan view of a bathroom scale embodying the design of my invention;

FIGURE 2 is a side elevational view of a bathroom scale shown in FIGURE 1, the other side being a mirror image thereof;

FIGURE 3 is a front elevational view of the bathroom scale; and

FIGURE 4 is a rear elevational view of the bathroom scale.

The characteristic feature of the design for a bathroom scale resides in the dial head portion.

I claim:

The ornamental design for a bathroom scale, as shown and described.
